UNITED STATES PATENT OFFICE.

ROBERT H. READ, OF SCHENECTADY, NEW YORK, ASSIGNOR TO GENERAL ELECTRIC COMPANY, A CORPORATION OF NEW YORK.

GLOBE-CLEANER FOR ARC-LAMPS.

No. 905,458.

Specification of Letters Patent.

Patented Dec. 1, 1908.

Application filed October 25, 1906. Serial No. 340,525.

To all whom it may concern:

Be it known that I, ROBERT H. READ, a citizen of the United States, residing at Schenectady, county of Schenectady, State of New York, have invented certain new and useful Improvements in Globe-Cleaners for Arc-Lamps, of which the following is a specification.

This invention relates to inclosed arc lamps in which the electrodes are of the magnetite or carbid order, which deposit a film of oxid on the inside of the inner globe. The deposit is a fine dust which forms very rapidly; fifteen minutes' service being sufficient with some electrodes to materially obscure the light.

It has been proposed in the case of carbon electrodes to use a mechanical cleaning device, operating automatically and periodically, and serving to wipe off the deposit. It is very doubtful, however, whether such an arrangement would be entirely effective with a carbon arc, as the carbon deposit adheres tenaciously to the surface of the globe. But with the flaming arcs, and especially with carbid electrodes, the deposit is easily removed, the lightest touch being sufficient to dislodge it.

My invention consists in certain mechanical constructions and arrangements whereby a wiper is caused to remove these deposits automatically. It is illustrated in the accompanying drawing, in which

Figure 1 is an elevation of an inclosed arc lamp, partly in section, and embodying my improved wiper; Fig. 2 is a section of the globe holder on a larger scale; Fig. 3 is a sectional plan view of the same; Fig. 4 shows the collar for supporting the wipers; Fig. 5 is a cross section of a wiper; Fig. 6 is a diagram of circuits; and Fig. 7 is a detail of construction of the lower operating mechanism.

The lamp may be of any suitable construction in which an inner globe 1 surrounds the arc. I support this globe by resting its lower end on a ring 2 provided with external screw threads to receive a union 3. A suitable cushion, such as a helical spring 4, is interposed between the union and the globe. The ring has an inwardly projecting flange 5 which is supported on a circular shoulder 6 on the stationary holder 7 for the lower electrode 8. It is preferred to groove the ring or the shoulder or both to

form a raceway for a set of balls 9, constituting a ball bearing for the globe support 2, and enabling it to revolve easily on the holder 7. Inside this rotatable globe are arranged a pair of stationary wipers. I prefer to use two though it is evident that a less or greater number may be provided if desired. Each wiper consists preferably of a wire 10 surrounded with asbestos 11, or some other soft and refractory substance. The upper ends of the wipers pass pivotally through holes in the gas-cap 12, and are provided above said cap with small handles 13. The lower ends of the wipers are supported in a stationary part of the lamp, being preferably journaled in a collar 14 of non-conducting material, such as porcelain, which fits loosely upon a polygonal neck or projection 15 extending up centrally from the holder 7 and surrounding the lower electrode. The ends of the wires 10 may be headed to prevent their pulling out, and the heads may be received in notches 16 in the under side of the collar 14; said notches being filled with cement to insulate the wires, as shown in Fig. 2.

The wipers are curved to rest easily against the inside of the globe 1, and are preferably located in the plane of the hangers 17 of the lamp frame, so as not to cast any additional shadows.

In order to revolve the globe, I prefer to use an electric motor, such as the electromagnet 18 in shunt to the lamp. The armature 19 of said magnet carries one of a pair of contacts 20 in the circuit of said magnet. A spring 21 retracts said armature to close said circuit, but the closing movement is retarded by a time-limiting device, such as the dashpot 22, which, however, offers no obstruction to the quick attraction of the armature when the circuit of the magnet is finally closed. It will be seen that this construction operates like an electric bell, but at a slow rate. The electromagnet is conveniently mounted in the upper part of the lamp, as shown in Fig. 1. The armature is attached to the upper end of a long shaft 23 which runs down to a point near the holder 7 being journaled in bearings 24 secured to the hanger 17. On the lower end of the shaft is an arm 25 carrying a pivoted pawl 26. A spring 27 keeps said pawl in engagement with a ratchet wheel 28 on a short upright shaft 29. A pinion 30 on said shaft meshes with an annular

set of teeth 31 formed on the periphery of the ring 2.

The operation is as follows: At every energization of the electromagnet 18 the pawl 26 actuates the ratchet wheel 28, and causes a partial rotation of the globe support and globe. Since the wipers are journaled at the upper end in the gas-cap 12 and at the lower end in the collar 14, they are liable to be 5 swung aside by the drag of the globe. To prevent this, each handle 13 is prevented from movement in one direction by a pin 32 in the gas-cap, so that the wipers are held in operative relation to the globe. Inasmuch as 10 the wipers remain stationary, the slow intermittent rotation of the globe carries its entire surface past them at every half revolution, thus effecting a steady and continuous cleaning off of the deposit. The accumulation 15 of dust in the bottom of the globe can be emptied out whenever the lamp is trimmed.

When the globe is to be removed, the wipers are turned in towards the electrodes by moving the handles 13 away from the pins 25 32, as shown in dotted lines in Fig. 1. The globe holder can then be lowered by loosening screws 33, 33^a and dropping the frame in guide tubes 17. When lowered the collar and cap 12 may be slipped off the neck 15 30 and the globe then removed and emptied. When the globe and wipers are replaced, the collar will be guided to its seat on the neck by the lower carbon and the sides of the globe into the lower end of which it fits easily, as 35 best shown in Fig. 2.

What I claim as new and desire to secure by Letters Patent of the United States, is,—

1. In an inclosed arc lamp, the combination with the inner globe, of one or more 40 wipers therein extending lengthwise thereof and conforming to the profile of the globe.
2. In an inclosed arc lamp, the combination with the inner globe, of a wiper therein which conforms to the profile of the globe,

and means for effecting a relative rotating 45 movement of the globe and wiper.

3. In an inclosed arc lamp, the combination with the inner globe, of one or more stationary wipers therein, and means for revolving the globe. 50

4. In an inclosed arc lamp, the combination with the inner globe, of a rotatable support for said globe, means for rotating it automatically, and one or more stationary wipers inside said globe. 55

5. In an inclosed arc lamp, the combination with the inner globe, of electromagnetic means for rotating it, and one or more stationary wipers inside said globe.

6. In an inclosed arc lamp, the combination with the inner globe, of electrical means for rotating it step by step, and one or more stationary wipers inside said globe. 60

7. In an inclosed arc lamp, the combination with a rotatable inner globe, of one or 65 more stationary wipers inside the same in the plane of the hangers supporting the lower electrode.

8. In an inclosed arc lamp, the combination of an inner globe, a wiper, and means 70 for automatically effecting a slow relative movement to remove the deposit.

9. In an inclosed arc lamp, the combination of an inner globe, a wiper, and means for automatically effecting a slow relative 75 rotary movement of the two parts to remove the deposit.

10. In an inclosed arc lamp, the combination with a rotatable globe support, of an electromagnet in shunt to the lamp, and 80 means whereby said magnet can rotate said support.

In witness whereof, I have hereunto set my hand this 24th day of October, 1906.

ROBERT H. READ.
